N. J., a corporation of New Jersey

Application December 6, 1950, Serial No. 199,437

22 Claims. (Cl. 340—356)

1

This invention relates to keying apparatus such as employed for keying an electrical control circuit in a signal transmitting system or the like, and more particularly relates to keying mechanisms where a desired message is set up and wherein operation of the mechanism then produces successive actuations of electrical contact means, i. e. a keying switch, to translate the message into appropriately keyed operation of the control circuit. In such devices, the keying operation is preferably automatic, as under a motor drive or the like, and such that the message-keying cycle is automatically repeated, e. g. for successive transmission or signaling operation with respect to the same message. In a more specific sense, the invention is concerned with such keying apparatus in which the message may be readily set up by adjustable means or by other manipulation, permitting ready change or substitution of messages, a particularly important and preferred embodiment of the apparatus involving the use of settable message-defining members so that any of an essentially infinite variety of messages may be selected.

Keying apparatus of such character is useful for a wide variety of purposes, especially in situations where any one of many conceivable messages, depending on circumstances, may have to be transmitted, i. e. keyed, automatically and repeatedly. It may be explained that for the purpose of the present specification and claims, the term "message" is used to mean any series of character elements which can be translated into a corresponding series of modifications of one or more electrical circuits, each such series of character elements customarily involving a multiplicity of them so arranged in succession as to afford a series of control components having individual durations or successive spacing in time, which usually differ, e. g. in relation to each other, as the series progresses. The arranged series of character elements, in themselves or by successive arrangement providing the series of control components, thus represents the distinctive character of the message. Thus, for example, such message may consist of a series of letters or other characters in the International Morse code, which may spell out one or more words of ordinary intelligible nature, or may consist of a combination of letters or numbers having some special significance. The dots and dashes composing the characters in such code, and likewise the spaces between such parts of a character and between characters, may thus represent the control components of a message

2

to be keyed, the term "character elements" being used herein in a generic sense to define such components or, for example in the case of the stated code, more elemental parts of which the dots, dashes and spaces may be deemed to be composed. Thus a message in code of this type can be analyzed or established as a series of two types of character elements, viz. a dot unit and a space unit, with dashes and spaces between letters being composed of a plurality of such units respectively.

Alternatively, apparatus of the nature hereinbelow described may be employed for the keying of messages which consist of other than Morse code characters, e. g. another series of a multiplicity of character elements (as of the above described or some other nature), having predetermined significance for signaling, remote controlling or like operations. It will thus be understood that the term "message," while customarily involving a more complex succession of character elements than, say such as would require only a single alternation or like simple operation of circuit control, is not necessarily restricted to a series of words, abbreviations or the like having direct literary significance.

By way of example, a keying mechanism of the present and preferably adjustable type is of special utility for sea, air or other vessels which are required to transmit any one of a multiplicity of predetermined or otherwise specially delineated messages, as by radio, light signal or the like, to indicate the location of the vessel in a particular area or to transmit a standardized request or statement of information to a remote observer. In such situations it is quite commonly contemplated that the selected message be repeatedly signaled, i. e. transmitted again and again throughout a relatively long interval of time. Quite frequently, such messages may consist simply of a combination of letters or numbers in accordance with a special signaling code. For such use, a device of the present sort may sometimes be described as an adjustable or variable code keyer, in permitting any one of many code combinations of characters to be set up for transmission. To avoid confusion, however, such combinations are herein described as messages, the term "code" being generally restricted to the sense of the International Morse or like code, directly employed for electrical circuit control.

Devices of the described type are often employed under severe service conditions and by personnel who may have many other duties, so

that complete reliability of the equipment and ease of its operation are of great importance. The setting up of a message should preferably be performed with speed and facility, requiring no special training of the operator and involving no complex mechanical adjustments. Likewise the device should be rugged, precise and reliable in operation and in all respects such as to minimize any need for repair, adjustment or replacement of mechanical and electrical parts. Compactness of design and quietness in operation are also important criteria, especially where the apparatus must be located in spaces where other communication and signaling equipment is carried and more or less constantly employed.

Important objects of the present invention are therefore to provide apparatus of the character described, achieving all or at least some of the above criteria of structure and operation. A specific and particularly important object is to provide such apparatus wherein by simple manipulation of settable members, e. g. wholly from the exterior of the device, any of a variety of messages may be established, in an improved and notably convenient manner. A still further object is to provide novel and effective apparatus of the type described wherein the actual electrical keying operation is performed by only a single switch or equivalent device, in accordance with the desired message, thus avoiding servicing or other problems incidental to the use of a multiplicity of electrical contacts, for example, corresponding to successive parts of messages. A corresponding object is the provision of improved apparatus wherein except for the keying switch itself, the setting, translating and control operations are all achieved by mechanical means, which may be of a relatively reliable character, positive in function at all times and substantially non-susceptible of derangement or misadjustment.

Another object is to provide keying apparatus of new and efficient nature, which is especially quiet in operation, which is of compact yet rugged character and which requires only a relatively small amount of power for automatic operation, e. g. thus permitting the use of a relatively small and inexpensive motor for its drive and thus also minimizing wear and tear on various moving or bearing parts.

Additional objects are the provision of improved devices of the stated type, which are more efficient and economical, easier to operate, and simpler or otherwise less expensive to manufacture, as in the foregoing or other respects, and in comparison with such equipment as may heretofore have been available for like purpose.

To these and other ends, important features of the improved apparatus, especially as embodied in presently preferred forms, of the sort hereinbelow described, include the provision of a readily settable structure, e. g. a series of settable members, extending along a linear path or paths and adapted to define the desired message by surface contour of the structure along the path, as by successive high and low faces of the component members. In cooperation with the message-defining structure, sensing means are provided, progressively movable along the path for positional response to the selected contour of the elongated structure or assembly. Cooperating with the sensing means and thus functioning throughout its progress along the path, means are provided to actuate a keying switch, viz. an electrical contacting device (or assembly

of devices), which can be shifted to and from a plurality of positions for corresponding modification or like control function with respect to one or more electrical circuits.

In the instrumentalities for sensing the control components of the message structure and thereby successively operating the switch, and especially in the case of message-defining structures arranged in one or more rectilinear rows, one very advantageous arrangement comprises an elongated device, arranged parallel to the path or paths along the message means, and reciprocable in accordance with the positional response of the sensing means as it progresses from one end to the other of the path or paths. In accordance with certain presently preferred and specific aspects of the invention, the mechanism includes one or more sensing members having provision, such as a conveyor device, for carrying the member or members along the message structure and in positionally responsive relation thereto. The elongated actuating member, in such arrangement, is preferably constituted by a platen or the like disposed along the path of the sensing element, at its other side, and mounted, e. g. by parallel linkage, for reciprocation by the sensing element at any locality of the latter in the path, means being provided for transmitting the platen displacements to the keying switch, so that successive actuations of the latter are effectively achieved during the travel of the sensing means. Provision is also preferably made for automatic drive, i. e. to carry the sensing means along the designated path, for instance by an electric or other motor suitably coupled to the conveyor device. A further and likewise important feature of the present improvements involves the provision of two or more message structures, e. g. each of the sort mentioned above, arranged in parallel, coextensive relation, the conveyor device then carrying separate sensing elements respectively past one and then another of the message structures. In this way messages of considerable length may be established for transmission with mechanism of notably small and compact size. Further features of structural or other improvement, and likewise additional details of instrumentalities mentioned above, are disclosed in the specific examples of mechanisms set forth below, all to the attainment of efficient, reliable and easily controlled keying operations.

The accompanying drawings thus illustrate certain specific structures embodying the invention and designed for automatic keying of any of a wide variety of messages that may be set up by means of simple, keyboard character.

Referring to the drawings:

Fig. 1 is a plan view (or elevation if the device is disposed in upright position) of the outer or panel face of a presently preferred embodiment;

Fig. 2 is essentially a vertical section (considering Fig. 1 as in plan) on line 2—2 of Fig. 1;

Fig. 2a is an enlarged fragmentary view of a part of Fig. 2, showing certain detail of releasable retaining means for the settable members;

Fig. 2b is an enlarged fragmentary view of another part of Fig. 2, but showing certain functions of a sensing device in another position;

Fig. 3 is a horizontal section on line 3—3 of Fig. 2, with certain structure broken away to reveal underlying parts;

Fig. 4 is a transverse section on line 4—4 of Fig. 2;

Fig. 4a is an enlarged fragmentary view of a

part of Fig. 4, further showing detail illustrated in Fig. 2a;

Fig. 5 is a somewhat fragmentary view corresponding to Fig. 1 and thus conveniently considered in plan, of structure on the outer or panel face of another embodiment of the invention;

Fig. 6 is a fragmentary vertical section on line 6—6 of Fig. 5;

Fig. 7 is a transverse vertical section on line 7—7 of Fig. 5;

Fig. 8 is an elevational view (or horizontal view if the panel of the device is upright) of another embodiment; and

Fig. 9 is a fragmentary sectional view, taken as if on line 9—9 of Fig. 8, but with the vertical dimension of Fig. 9 taken perpendicular to the plane of the drawing of Fig. 8.

Referring first to Figs. 1 to 4, inclusive, the particularly advantageous type of mechanism there shown is designed for automatic keying of any desired message that may be set up, for example, in International Morse code on a key board generally designated 20 and exposed at the outer face of a panel 21 which may also constitute an outer or upper supporting plate for the mechanism. It will be understood that the device may be mounted or disposed with the panel 21 in vertical, horizontal or other desired position.

In the illustrated structure, the key board 20 consists of three parallel rows 22, 23 and 24 of keys or settable members 25, each consisting of an exposed head so identified, carried at the outer end of a rod or shank 27 which slides through a corresponding opening 28 in the panel 21 and which is also guided by an aligning hole or opening 30 in a subpanel 31 mounted behind the main panel in spaced relation thereto. Thus, each of the rows 22, 23 and 24 comprises a linear array of the keys 25 in essentially side-by-side relation along a predetermined straight line.

At its inner end each of the key shanks 27 carries a cylindrically shaped head or abutment 32, providing a plane face 33 exposed in an opposite direction from the panels 21, 31 and designed to constitute an elemental part of the message-defining contour as further explained below. Each of the key devices is thus shiftable perpendicularly of the panel 21, selectively into a plurality of positions respectively representing actuating levels to be transmitted to the keying switch and respectively corresponding to the plurality of operating positions employed in the switch and desired for character-defining transmission of character elements. Thus for example, where the transmission is to be in accordance with the stated Morse code and the circuit modification (as by opening or closing one or more circuits) is to reciprocate between a position for dots and dashes and a position for spaces, each of the keys 25 is shiftable between two control positions, i. e. between a high position of its face 33 as at 33a in Fig. 2, or a low position of such face as at 33b, the terms "high" and "low" being used with respect to the path of sensing means across the message faces 33 of the keys as also described below.

Means are provided for releasably locking each key in each of its selective positions. Thus a coil spring 35 is disposed under compression around each key shank 27 between the subpanel 31 and a collar 36 held on the key shank by a pin 37, each spring 35 thus urging its corresponding key outwardly into the low position of the control face 33. To cooperate in holding the key in such outer position, the projecting ends of a pin 38, which is

mounted in the key shank at a locality spaced from the head 32, abut the lower side of the subpanel 31 and are specifically designed to seat in a groove 40 (Figs. 2a and 4a) formed in the surface of the subpanel and extending along the line of the holes 39. For clarity, the arrangement of the groove is omitted from Figs. 2 and 4, but shown in detail in the enlarged views of Figs. 2a and 4a.

To hold any one of keys with its face 33 in the high position, there is provided a flange or rest 42 extending alongside each of the rows 22, 23 and 24 at the lower or innermost face of the subpanel 31. Adjacent each key shank 27, the flange 42 for the corresponding row carries a notch 44 of a size to receive one projecting end of the pin 38. Each key rod or shank 27 is adapted to turn as well as slide in the holes 28, 30, as by manual rotation of the key head 25. Thus for example, to displace one of the keys from its low face position at 33b to a high face position at 33a, the head 25 is depressed until the pin 38 is well below the edge of the adjacent flange 42, whereupon the key is turned 90° and allowed to move outwardly, seating the pin 38 in the corresponding notch 44. By such operation, the key is releasably locked with its operating face at a high position 33a. To move such a key back to the alternative position, it is simply again slidably depressed, clearing the pin from the flange 42, and then turned 90°, whereupon it may be released to reseat the pin in the groove 40, where it is now releasably locked in a low position, the spring 35 again holding the key at such location.

While the corresponding elevated and depressed positions of the key heads 25 outside the panel 21 may serve to designate the positioning of the respective keys, each may also be provided with an index mark such as a transverse line 46 diametrically crossing its surface and disposed to indicate the position of the key and specifically the position of its operating face 33; since the releasable locking means requires the turning of the keys through 90° between the two positions of each, the attitude of the line 46, e. g. horizontal or vertical, will thus represent the key position.

While the index keys and their respective faces 33 may be designed to represent other types of character elements, a conventional arrangement (as in the specific device shown) is to have each key constitute a single unit of Morse code representation, viz, the dot unit in the high position 33a and a space unit in the low position 33b. As will now be apparent, a dash is constituted by depressing three (or more) adjacent keys 25 to the high position of the operating face as at 25a, while a dot is afforded by a single key so disposed as at 25c. Likewise, a space between the control components of a single letter or other character, e. g. between the dots and dashes of a given letter, is afforded by the low position of the face 33 of one key, e. g. as at 25b, while a space between characters or letters is represented by the corresponding low position of a plurality of faces 33, for example, a group of three keys as indicated at 25d. It will now be seen that various dots, dashes, spaces and like control components of various lengths may be readily provided by manual setting of the successive members or keys 25 in the above described manner along the several rows 22, 23, 24. The index lines 46 cooperate in representing the position of the key and indeed in affording visual designation of the dots, dashes and spaces, for instance by

disposing the lines so that a horizontal position of the lines represents a high position of the faces 33 (for dots or dashes) and a vertical line position designates spacing, i. e. where the face 33 is in its low position in the message contour.

As will presently appear, the apparatus is adapted to afford circuit-keying response to the successive control components settable on the lines 22, 23, 24 in succession, for example (as shown in Fig. 1) by progressing from the left hand end of line 22 to its right hand end in the direction of the dotted arrow, then in effect reverting in the direction of the curved index arrows to the left hand end of line 23. Thereafter keying proceeds along line 23 and finally shifts again, back to the left hand end of line 24 for like progress along the latter, the complete cycle being thereafter repeated in the desired automatic operation of the mechanism. Although the illustrated device is shown with three such rows of 20 keys each, it will be understood that the number of rows, whether one, two or more, and likewise the number of keys in each row, may vary considerably in accordance with the service for which the apparatus is designed and especially the kinds of message which it is required to transmit. For instance, where each message is to be expressed in a combination of 2 or 3 letters or numbers in the described Morse code, an arrangement of the sort actually shown is usually suitable; still simpler messages may require only a single row of keys while adaptability to longer or more complex series of character elements may necessitate longer rows of keys or a greater number of rows.

In order to effectuate sensing of the message-defining contour thus settable at the faces 33 along the rows of keys, suitable sensing means are carried past the paths of the faces by a conveyor device comprising a pair of endless chains 50, 51 which lie in respective loops spaced along and at opposite sides of the parallel paths corresponding to the rows 22 to 24. At one end, the chains are carried by corresponding spaced sprocket wheels 52, 53 on a shaft 54, and at the other end by like sprocket wheels 56, 57 fixed on the shaft 58. The shafts 54, 58 are supported by suitable bearing blocks 59 carried near the ends of a plate 60 mounted on the frame structure generally designated 61. Thus the sprocket chains 50, 51 are adapted to travel continuously in their parallel, defined loops, the chains travelling together and each traversing paths adjacent but outside several rows of key faces 33.

To provide sensing elements for engagement with the message-defining contours of the respective key rows 22 to 24, supporting rods 62, 63 and 64 are carried by and between the chains 50, 51, each rod having its ends respectively secured to the chains and spanning the distance between them in a direction perpendicular to the path across the rows 22 to 24, but adapted to lie in the plane of such path or paths. As indicated, one such rod is provided, in effect, for each of the key rows and carries a sensing element so disposed on the rod as to cross the face of a specific key row without engaging any other row. In the preferred device shown, the sensing elements comprise respectively the sleeves or tubular sections 72, 73 and 74, respectively mounted on the rods 62, 63 and 64 for coaction with the individual rows 22, 23 and 24.

Hence as the chains 50, 51 are advanced around their sprocket wheels as in the direction of the

arrows in Fig. 2, the sensing elements will be carried past the faces 33, each element being operatively engaged only with the row to which its position, on its corresponding supporting rod, relates. For instance, in Fig. 2, the sensing element 73 has just completed traversing the row 23 of key members (not shown, but behind the illustrated row 24), while the element 74 is about to pass its own key row 24. Thereafter, a new cycle of keying will be commenced (by continued travel of the chains) when the sensing element 72 reaches its own row 22 of faces 33. For completion of the succeeding cycle (the first cycle having been illustrated at a stage of partial completion), the respective sensing elements 73, 74 will successively traverse their rows 23, 24. In most cases and especially for compactness of the equipment, the chains 50, 51 may be no longer than to accommodate the required number of sensing elements with their supporting rods mutually spaced lengthwise of the chain by distances approximately equal to the lengths of the key rows, so that as soon as one cycle of three row message transmission is completed, the next cycle follows immediately. Manifestly, however, other spacing arrangements of the sensing means may be employed for specific purposes, for example, as by utilizing longer chains and providing greater chain-wise spacing thereon between the last and first elements 74, 72, i. e. to afford an interval of silence between successive repetitions of the message.

As will now be apparent, the chains are disposed to carry the sensing elements past the heads 32, for positional displacement or reciprocation of the elements perpendicularly to the path of travel, in accordance with the successive high and low faces of the message-defining structure. For transmission of the positional reciprocation of the sensing elements to actuate a keying switch as described below, a long platen 75 is provided, comprising a rectangular plate having a plane face parallel to the paths of the sensing means across the rows of key faces, the platen being arranged on the opposite side of the path, i. e. so that the sensing sleeves 72, 73 and 74 pass between it and the faces 33.

The platen 75 is provided with means mounting it for displacement only into positions parallel with itself. While other means such as telescoping studs or the like may be used, a pantograph type of structure has been found convenient, comprising four parallel links 77 each pivoted at its ends to corresponding ears 78, 79 respectively projecting from the platen and the lower mounting plate structure 60. The ears 78 are disposed in rectangular relation on the platen, and the ears 79 in similar relation on the plate 60, the disposition of the pivoted ends of the links 77 being staggered between the platen and plate 60 as shown, so that the links stand at a convenient operating angle (in the neighborhood of 45°) for displacement of the platen toward and away from the plate and thus with the plane of the platen moving perpendicularly to the path of the sensing means, as the links 77 swing in parallel about their pivots.

A projection 80 on one of the links 77 carries an adjustable stop screw 82 which is adapted to abut the face of the plate 60, preventing movement of the platen beyond a predetermined locality, i. e. in a direction toward the sensing path. A coil spring 84 under tension, extending between another of the links 77 and a post 85 that projects from the plate 60, resiliently urges the platen

outward, i. e. into position with its stop 82 engaged by the plate 60. Thus, depression of the platen away from the sending path must be exerted against the biasing action of the spring, which tends to restore the platen to its normal position shown in Fig. 2.

For actual keying operations in response to reciprocations of the platen 75, a switch generally designated 90 is included, being conveniently mounted on a plate structure 60 below or behind the platen. While any of a variety of switches may be employed, designed to perform single or multiple controlling operations (with respect to one or more electrical circuits) and responsive to two or more positions of reciprocation of the platen and sensing means, the drawings illustrate, for simplicity, an enclosed switch structure of the microswitch type. Likewise, merely for simplicity of illustration, the switch is diagrammatically indicated as including a pair of normally open contacts 92 adapted to be closed upon depression of a switch operating member or arm 93, the latter carrying an operating roller 94. Preferably the switch 90 is of a positive, snap-action type, quickly responsive to small displacements of its operating roller 94 in opposite directions, for successively reversed circuit controlling functions.

For actuation of the switch, its mounting is conveniently such that the roller 94 bears on the inner face of the platen 75, the roller being held or biased against the plate by suitable means such as spring means (e. g. a compressed spring, not shown, urging the member 93 outwardly) such as conventionally included in switches of the character described, it being understood that the switch 90 may in general be of conventional character as explained above. In consequence upon a slight downward displacement of the platen as seen in Fig. 2, the roller 94 is shifted downwardly (to dotted line position 94a), actuating the switch in one direction as to close the contacts 92, while upon return displacement of the platen, the switch arm 93 restores itself to the full line position of Fig. 2 and reverses the circuit control as by opening the contacts 92.

It will also now be seen that the described successive reciprocations of the switch are effectuated by the travel of one or another of the sensing means along a row of key faces 33. For instance, when the sensing element 74 (Fig. 2) travels to the right, striking the heads 32 of the dash group 25a, and passing beneath their faces 33, the platen is moved downward, being held in its lower position until the sensing element reaches the last of the three high faces. The corresponding actuation of the switch is effective to transmit a dash signal, terminated when the element 74 reaches the next space or low position of the settable faces 33 and the platen is accordingly permitted to shift to its outer or upper location. Succeeding high levels of faces 33 results in corresponding successions of contact actuation, through the intermediary of the platen in engagement with the roller 94. It will be particularly noted that the broad and elongated structure of the platen provides firm engageability for each of the three sensing members throughout the entire path of each, while the parallel linkage 77 permits only the same displacement of the platen, in response to a high face 33a, at all positions of the sensing elements. In consequence, uniform and positive actuation of the switch is always achieved.

While for some purposes the sensing elements 72 to 74 may be rigidly mounted on their sup-

porting rods 62 to 64 and may have other provision for displaceability (as by the flexibility of the chains themselves or by other arrangement) the illustrated loose fit of the sleeves on the rods is of special and novel advantage. That is to say, as shown more clearly in Fig. 2b, each of the sleeves such as sleeve 74, has a considerably larger inside diameter than the surface of its supporting rod such as 64, the sleeve being thus loosely carried on the rod but retained endwise by collars 96 fixed to the rod. Not only does the loose relation of the sleeve thus insure its displacement for actuation of the platen and switch, but the arrangement permits a more effective response to low faces 33b, e. g. to spaces in the illustrated sequence of dots and dashes.

As shown in Fig. 2b and assuming that the rod 64 is travelling in the direction of the arrow, it will be seen that whereas the sleeve 74 may only travel a short distance during the time that it lies wholly between two spaced high faces 33a, 33a, the distance of travel of the rod 64 is considerably greater, thereby providing a time interval for low position of the sleeve 74 at the low face 33b which more precisely represents the extent of such face in proportion to the high faces 33a. Thus this arrangement of the sensing elements permits a relatively large cylindrical element to be employed for ease of travel past successive high and low faces, yet avoids the reduction of the low face control intervals to objectionably small duration such as might occur (especially when the switch 90 is of snap-action type) were the sleeves or rollers fitted closely on the rods and such as might confuse the message transmission by making it difficult to distinguish the existence or length of spaces between the succeeding dots or dashes. The sensing element thus has a positional response which is equivalent to, i. e. as close as that of a much smaller element. Although when the switch is of a type that always makes and breaks its contact at the same point in its movement, close fitting rollers may sometimes be used, and although in some cases an appropriately slack chain may serve the special purposes of the loose fitting rollers or sleeves, it will now be seen that the latter represent a particularly effective structure for the described sensing operation.

It will be noted that the reciprocation of the sensing elements such as the sleeve 74 in Fig. 2b to the contour constituted by the high and low faces 33 need not involve actual abutment of the element with both face positions. That is to say, the return or upward movement of the platen 75 is limited by the stop screw 82 and it is therefore sufficient as shown in Fig. 2b that the sensing element ride somewhat inward (from the level of the high faces 33a) at the locality of the low faces 33b without actually touching the low faces.

For automatic operation of the apparatus a motor drive is provided, including an electric motor 100 of a conventional low power type carrying on its drive shaft 101 a gear 102 which meshes with a gear 103 on the shaft 58 for the sprocket wheels 56, 57. For control of the motor, a switch 104 may be provided on the panel 21, connected by suitable wiring (not shown). The motor circuit may also embrace a rheostat 105 which can be adjusted to vary the speed of the motor, and thus to change the keying speed of the apparatus. Although the rheostat can sometimes be mounted on the panel 21, adjustment is usually required at only infrequent times;

hence in the embodiment shown, access to the rheostat is had by removing the panel and the attached apparatus from the protective, metal housing 106. In some cases, for example when only a single keying speed is required, the rheostat can be omitted, the motor then preferably being of governor-controlled or synchronous type. Connections to all of the described electrical instrumentalities, such as the motor and the switch 90, may be effected by inserting a 10 suitable plug in a socket 107 on the panel.

It will be understood that the wiring connected to the electrical instrumentalities is not illustrated since it is not essentially a part of the present invention and may assume any form suitable to the conditions of service. Arranged as shown, the motor 100 is adapted through the indicated gearing to turn the sprockets 56, 57 and thus continuously advance the chains 50, 51, e. g. in the direction of the arrows (Fig. 2) for progressively moving the sensing means past the rows of message-defining faces of the key members.

For aid in use of the apparatus, and especially for the aid of inexperienced personnel, an instruction plate 108 may be mounted on the face of the panel 21, to show the manner of setting the keys for dots, dashes and various spaces, as well as to display a list of the Continental Morse (or other) code characters. It may be noted that whereas the above described and illustrated use of the keyer has assumed each dash to be equal to three dots, experience has shown that in many cases the so-called readability of the message is better with longer dashes, for instance composed of four (or more) dot-intervals, as obtained by depressing four (or more) of the keys 25.

The operation of the described mechanisms in Figs. 1 to 4 inclusive should now be evident. Assuming that the attendant desires to transmit a particular message or signal, he sets up the keys 25 in the several rows to represent the message, e. g. in Morse code characters as explained above. The message may extend consecutively through the rows beginning at the left hand end (Fig. 1) of row 22 and terminating at or before the right hand end of row 24. While a useful structure is possible with the settable members in one or more curved linear paths (e. g. concentric rows) and with the sensing means carried along corresponding orbits, the illustrated arrangement of the keys in parallel, straight lines is extraordinarily desirable, not only for economy of panel space and other structural advantage, but also for special convenience and simplicity in the visualization of the dot and dash message as it is set up.

With the several key members 25 set and releasably locked in desired high and low positions of the faces 33, the motor drive is initiated to carry the successive sensing elements 72 to 74, respectively along the rows, e. g. the three straight lines 22 to 24 shown in Fig. 1. As the chains constituting the conveyor complete a single revolution, the complete message set up on the rows of keys (or on one or more of said rows) is transmitted by desired successive actuations of the switch 90, and by the continuance of the motor drive, the entire signal is automatically repeated, transmitting the message again and again so long as the operator desires. To signal a different arrangement of character elements, i. e. a different message, the keys are simply manipulated to a new series of positions

and the operation proceeds as before; indeed if desired, a new message may be set up without arresting the travel of the conveyor device, assuming, of course, that no confusion results to the remote receiver through the brief interval of resetting.

The entire structure is of a rugged and reliable character, affording positive and uniform response in its mechanical translating system. The operation of setting up a message is extremely simple, involving manipulation of a convenient keyboard at a fully exposed locality and in a manner which inherently indicates the coding of the message at it is set up. There are no operations requiring tools or special instruments (as in the insertion or removal of cam segments or the like in a rotating circular cam), nor is the operator required to handle or adjust intricate electrical or like parts. Similarly, the electrical system represents a minimum of complexity, since a single switch or assembly of contacts may be used for all operations, i. e. for the entirety of each message and throughout any changes or resetting of messages; indeed in some cases, a sensing element of suitable structure and insulated mounting can itself be a contact for directly closing a circuit through the depressed keys. The apparatus is essentially light and compact, requiring a minimum of load on the motor 100 and needing little or no mechanical servicing over long periods of time.

Figs. 5 to 7 show another embodiment of the apparatus, involving some mechanical simplicity although lacking certain special advantages, e. g. in the case of setting up a message, attained with the device of Figs. 1 to 4. In Figs 5 to 7 the switch-actuating mechanism, including the sensing elements and conveyor structure, may be the same as in the apparatus first described, and is therefore not shown in detail again. Instead of the individually shiftable keys 25 permanently mounted in keyboard arrangement, the present embodiment has provision for one or more rows of replaceable members 110, 111, for instance three parallel rows 112, 113, 114, as shown. Each of the members 110, 111 has a rectangular shank portion 116 adapted to project through an elongated slot 112a, 113a, or 114a, in the panel or outer plate 118 of the apparatus, the slots thus corresponding with the above-mentioned rows of members settable to provide a message-defining contour. Each of the members 110, 111 also has arms or flanges 120 projecting at opposite sides transversely of the row in which the member is disposed, the projecting portions 120 thus engaging the face of the panel 118 to retain the member in a desired position against inward displacement. At its outer end, each of the members has a head, designated 122 or 123 for the members 110 and 111 respectively, and having a cross section smaller than the flanged portion 120, the heads 122, 123 being adapted to extend through a mounting slot in an outer panel or frame 125.

While other configurations of the members 110, 111 may be employed to afford the relation of various portions as described above, the elongated cross-shaped structure shown is particularly convenient, in facilitating the setting of the members and in promoting their proper alignment. As will also be apparent from the drawing, the members 110, 111 are respectively of different lengths below their projections 120; for example, the members 110 have a longer shank 116 so as to provide at the lower end a high face 126,

while the shorter shank 116 of the members 111 affords a corresponding low face 127. In consequence a series of members 110, 111 may be arranged in each of the rows 112, 113, 114, in varied succession so as to provide any desired order of high and low faces 126, 127 along the path of the corresponding sensing means such as the sensing element 130 shown by way of illustration.

As will also be apparent, the members 110, 111 may each be of a variety of lengths in a direction along the row. That is to say, there may be members 110 having a short face 126 to provide a dot of the coded message, and corresponding members, such as indicated at 110a, which are of elongated character and thus provide a high face extending for a longer distance, e. g. to represent a dash. Similarly, the low faces 127 of the members 111 may be short or long, in accordance with corresponding dimensions of such members lengthwise of the row, the short members serving to provide spaces between dots and dashes of a single character, and the long members affording spacing between characters. Alternatively, if desired, all of the members may be of uniform, short dimension, lengthwise of the message path, for instance so that each member represents the duration of a dot or of a space within a character, and so that dashes or longer spaces may be composed by a series of like members, just as such representation is obtainable by corresponding series of identically adjusted key members in Figs. 1 to 4. For variety of illustration, however, the structure shown in Figs. 5 to 7 embodies assemblies of members of different length, which each in itself constitutes an entire control component for effectuating a set of successive, alternate operations of the key switch.

The outer plate 125 serves to hold the members in place in the desired rows, by virtue of the corresponding slots 112b, 113b and 114b, arranged in registration with the slots of the plate 118 and thus seating over the heads 122, 123 of the settable members 110, 111. The plate or frame 125 is removably supported by screws 131 having manually engageable heads 128 and threaded into the panel 118. As shown, the plate 125, along the edges of the rows 112b, 113b and 114b seats on the upper edges or faces of the projections 120, thus retaining the key members 110, 111 against outward displacement. If desired, accurate positioning of the plate 125 and avoidance of undue pressure on the members 111 may be facilitated by spacers 129 through which the screws 131 pass intermediate the plate 125 and the main panel 118.

It will now be seen that in order to set up a desired message on the device of Figs. 5 to 7, the panel 125 is first removed by loosening the four screws 131 (indicated by their heads 128 in Fig. 5) so that the screws are free of the panel 118. Thereupon, from a suitable supply of members 110, 111, which may each be available in both long and short sizes if it is desired to utilize preset dash or long space elements, the operator selects a series which will represent a desired message, say in the Morse code, and inserts the members in proper, abutting sequence along the several rows 112, 113, 114. Since the operation of the sensing and key-actuating means is the same as in Figs. 1 to 4, the message may be established along the rows in sequence, as to read from left to right of row 112, then similarly for rows 113 and 114 in succession. Proper makeup of a desired message may be facilitated by dif-

ferently coloring or marking the high face key members 110 and the low face key members 111, for example by coloring the heads of the members 110 black to indicate dots or dashes, while the members 111 are colored white or left with unfinished metal surfaces.

When the members have been properly inserted and aligned, the plate 125 is replaced, seating its slots over the corresponding three rows of members, with their heads entered in the slots. Upon tightening the screws 131, the assembly is locked in place, ready for the transmitting operation. It will be noted that the slots preferably have a length equal to a whole number multiple of the short or narrow key members, and that where used, the elongated members (representing dashes or long spaces) are likewise dimensioned to equal a whole number multiple of the narrow members; thus each slot may be effectively filled, from end to end, with the members in any arrangement, subject to the inclusion of some extra spacing if necessary, as by one or two of the narrow members.

With the message thus established in the rows 112, 113, 114, the series of high and low faces provided at 126, 127 along the inner surface of each row may be sensed by appropriate means successively traversing the rows, for actuation of the key switch in accordance with the contour thus provided. As explained, it is assumed that the remaining parts are the same as shown in Figs. 1 to 4, including the conveyor chains 50, 51 for moving the sensing means, here represented by the element 130 (like the elements 72, 73, 74) carried by a transverse rod 132 between the chains and adapted to engage the surface of the platen 75. Thus as the sensing element 130 goes past its corresponding row, the platen 75 is shifted outward as the element passes a high face 126, and returns inward as the element reaches and traverses a low face 127. As shown in Fig. 2 and described hereinabove, the key switch is correspondingly actuated to transmit the desired message or signal. Since in the embodiment here shown the sensing element 130 need not actually abut the low faces 127, the members 111 may, if desired, be relatively shorter than as illustrated in Fig. 6, a short shank of such member being thus indicated, by way of example, at 116a in Fig. 7.

When a different message is to be keyed, the plate 125 is simply again removed and a new combination of members 110, 111 set up in the slots. As will now be apparent, the structure of Figs. 5 to 7 affords a simple and relatively convenient means for ready establishment of any desired message for automatic keying, although the structure lacks certain specific advantages, such as rapidity of adjustment or setting, and absence of separable parts, that characterize the device of Figs. 1 to 4.

As indicated above, structures of the present sort may have any desired number of rows of settable members, arranged to be successively traversed by sensing means for control of the keying switch. Figs. 8 and 9, for example, show an arrangement otherwise similar to Figs. 1 to 4 but embodying four parallel rows, 141 to 144 inclusive, of key members 25, each having the same structure, and mounting and locking arrangements as shown in detail in the earlier figures. In order to provide four successive sensing means on the endless conveyor device comprising the pair of spaced, parallel, endless chains 150, 151, the chains must be proportion-

ately longer than the chains 59, 51 of Figs. 2 and 3. Fig. 8 shows one provision for accommodating longer chains, i. e. by providing a supplemental pair of sprocket wheels indicated at 152 and spaced rearwardly of the like chain-supporting wheels 153, 154 that are disposed at the ends of the path behind the keys. The extra sprocket wheels 152 may be carried on an appropriate shaft 155, supported by suitable arms or like structure indicated at 157. In consequence the loop followed by each of the chains 150, 151 has a generally triangular contour, extending rearwardly of the message-defining path as well as along the latter, so as to provide the desired, greater length for the conveyor.

By reason of the described structure, four sensing elements 161 to 164 inclusive, may be carried by the chains, mutually spaced by a distance equal to the length of a key row, for the desired, successive response to the four rows. It will be understood that where still greater numbers of sensing elements are required, as for more rows, longer conveyor devices may be employed, including appropriate provision for suspension or support of the idle parts of the conveyor through regions at the rear of the message-defining paths or otherwise spaced from such paths, additional sets of sprocket wheels being thus provided as necessary to accommodate the longer chains. It will also be understood that the operation of the device of Fig. 8 is otherwise identical with that of the other figures, in that the plate 75 is reciprocated in accordance with the message defined by each row of members, for actuation of the keying switch 90.

It is to be understood that the invention is not limited to the specific apparatus herein shown and described but may be embodied in other forms without departure from its spirit.

I claim:

1. Keying apparatus comprising a keying switch, a plurality of members disposed in a linear array and shiftably arranged to constitute an elongated, stationary linear structure having a message-defining contour, sensing means movable along said structure for positional response to said members in succession from one end to the other of said structure, and switch-actuating means including an elongated member extending substantially the length of and parallel to said structure and displaceable mechanically by the sensing means throughout the movement of the sensing means along said structure, for operating the switch in accordance with the defined message.

2. Keying apparatus comprising a keying switch, means including structure disposed along a predetermined rectilinear path, to provide a message-defining contour along said path, and switch actuating means including sensing means movable progressively past said structure and means mechanically controllable by the sensing means throughout the path, for operating the switch successively in accordance with positional response of the sensing means to the aforesaid contour, said sensing means comprising a supporting member disposed transversely of the path but movable along the path, and a tubular element substantially larger than the member and loosely carried on the member and adapted to engage the aforesaid contour of said structure, the loose mounting of the tubular element providing positional response of the element to said contour equivalent to an element of substantially smaller size.

3. Keying apparatus comprising a keying switch, a panel, a plurality of members disposed in a linear array on one side of the panel and having manually engageable portions extending through the panel to the other side, each of said members being shiftable transversely of said linear array selectively into high and low positions, whereby said plurality of members is adapted to be set up to constitute said array as a linear structure having a message-defining contour, sensing means movable in a path along said linear array, for positional response to said members in succession from one end to the other of the structure, and switch-actuating means including a platen which is mounted to move only in a direction transverse of said path and is engageable by said sensing means throughout said path along the linear array, for operating the switch in accordance with a message defined by said structure.

4. Keying apparatus comprising a keying switch, a plurality of settable members aligned in stationary array along a predetermined linear path to provide a message-defining contour along said path, and switch actuating means including sensing means movable past said members in succession along the path and means mechanically controllable by the sensing means throughout the path for operating the switch successively in accordance with positional response of the sensing means to the aforesaid contour, some of said members being disposed with a control face in position to be engaged by said sensing means for a predetermined stroke of said switch and others of said members being arranged to be ineffective for said predetermined switch stroke, and each of said members being individually settable and having a part extending away from said path and accessible for individually setting the member in desired position in the path.

5. Apparatus as described in claim 4 in which the settable members comprise members having successively different lengths transversely of the path and thereby having corresponding high and low end faces at said path to constitute the aforesaid contour, each member being removably settable in the aforesaid aligned relation along the path, and the members being replaceable by other like members to be set in the path for provision of a different message-defining contour, said apparatus including means releasably engaging the aligned, set members as a group, to hold them in position.

6. Apparatus as described in claim 4 in which each of the settable members comprises a key member having an end face adjacent the path and shiftable transversely of the path selectively into high and low positions of the end face, and means for releasably holding each key member in each of its selectable positions.

7. Keying apparatus comprising a keying switch, a plurality of individually settable members disposed in a stationary linear array along a predetermined path and adapted to provide successive high and low faces along said path to define a message, and translating means controlled by said members and comprising sensing means movable along said path for positional response to said high and low faces in succession, switch actuating means mechanically controllable by said sensing means throughout its travel along said path and in accordance with positional response of the sensing means to the aforesaid high and low faces, and means includ-

ing a panel, for supporting the members in said linear array, said members consisting of some members each of which has a single high face exposed in said path, and some members each of which has only a low face exposed in said path, each of said members having a part extending away from said path and accessible at the face of the panel for individually setting the member in desired position in the path.

8. Keying apparatus comprising a keying switch, a plurality of parallel, rectilinear rows of settable members, each of said rows comprising a plurality of members arranged to provide a series of high and low faces along a corresponding rectilinear path, to define a message, the rows of members being disposed so that the corresponding rectilinear paths lie parallel to each other in substantially the same plane, a plurality of sensing means corresponding to the plurality of rows of members, each sensing means being adapted for positional response to the high and low faces of the members in the corresponding path upon movement of such sensing means along said path, an elongated conveyor device having a length at least equal to the length of a row of members multiplied by the number of such rows, the sensing means being carried by the conveyor device at localities spaced along the latter by distances at least equal to the length of a row of members, means for advancing the conveyor device lengthwise along the aforesaid predetermined paths, so that the sensing means are successively carried along the respective corresponding rows of members for positional response thereto, and switch-actuating means including a control structure therefor disposed to be actuated by each of the sensing means throughout its path along the said members.

9. Keying apparatus comprising a keying switch, a plurality of settable members disposed in a linear array along a predetermined path, each of said members having a single face exposed at said path, each of said members being shiftable transversely of said path to dispose its aforesaid face in high and low positions, means for releasably holding the members in their respectively selected positions, sensing means movable along the path for positional response to the high and low positions of said faces, and switch-actuating means controlled by the sensing means in accordance with successive positional displacements thereof, each of said members having its aforesaid face adapted, when in high position, to be engaged by the sensing means, and the members being collectively adapted to provide, by the high faces, a series of spaced message-defining dots and dashes, the members being closely spaced to constitute a continuous dash by the setting of a plurality of adjacent members in high position.

10. In keying apparatus, in combination, a plurality of settable members disposed in a linear array and arranged to present a series of high and low faces along a predetermined path, sensing means movable along the path and positionally responsive to said high and low faces, and translating means including a platen mounted independently of the sensing means and disposed to be engaged by said sensing means throughout said path and shiftable only in a direction transversely of the path, in accordance with positional response of the sensing means to said faces, said sensing means, as it traverses said path, being movable along and relative to said platen.

11. Keying apparatus comprising a plurality of

settable members disposed in a linear array and arranged to provide a series of high faces and spaces characterized by absence of a high face, along a predetermined path to designate a message, a sensing device adapted to engage said faces and shiftable in accordance therewith, conveyor means for moving said sensing device along said path in responsive relation to said faces, and switching means including a switch and control structure therefor, said control structure extending lengthwise of said path and being adapted to be displaced by the sensing means in accordance with the positional response thereof to the message-defining faces along the path, said conveyor means comprising an endless conveyor device and means for continuously advancing said device along a corresponding endless path which includes the aforesaid predetermined path, said sensing means being carried by the conveyor device intermediate said settable members and the control structure displaced by the sensing means.

12. Apparatus as described in claim 11 wherein the conveyor device comprises a pair of endless chains adapted to pass along spaced paths parallel to the first-mentioned predetermined path, the sensing means including supporting structure mounted at its ends to the respective chains, and the control structure displaced by the sensing means comprising a platen extending along the first predetermined path and mounted for displacement only in a direction transverse to said path for response to positional displacements of the sensing means.

13. Keying apparatus comprising a keying switch, a plurality of settable members disposed in stationary linear array along a predetermined path, each of said members having a face exposed in said path and being shiftable transversely of the path in a direction perpendicular to said face, between respectively selectable high and low positions, each member having associated spring means biasing the member into one of said positions and releasable retaining means for holding the member in the other of said positions against the biasing effect of the spring means, sensing means adapted to traverse the path for positional response to the members in succession, and switch-actuating means mechanically controlled by the sensing means and in accordance with positional displacements thereof.

14. Keying apparatus, comprising a keying switch, a plurality of individually settable members disposed in stationary, linear array along a predetermined path and arranged to provide a series of faces engageable in said path and spaces characterized by absence of an engageable face, to designate a message, sensing means adapted to traverse the path for positional response to the members in succession, switch-actuating means mechanically controlled by the sensing means and in accordance with positional displacement thereof, and means for repeatedly advancing the sensing means along said path in positionally responsive relation to the faces of the members, the switch-actuating means comprising a platen extending lengthwise of said path in parallel relation thereto, said platen being engageable by the sensing means.

15. Apparatus as described in claim 14 in which the means for repeatedly advancing the sensing means comprises an endless conveyor device to which the sensing means is mounted, and means for continuously advancing said conveyor device along a corresponding endless path which includes the aforesaid predetermined path, to carry

the sensing means repeatedly along the members, between them and the platen.

16. Apparatus as described in claim 15 which includes another plurality of settable members disposed along a linear path parallel to the first-mentioned path, said members of said second row being identically mounted and structurally identical with the members of the first row, and a second sensing means adapted for positional response to the faces of the members of the second row, the platen being disposed for actuation by each of the sensing means and the conveyor device carrying the second sensing means in spaced relation lengthwise of said device, for advancing of the second sensing means along said path and in positionally responsive relation to the members of the second row after the first sensing means has traversed the path.

17. In keying apparatus, in combination, a plurality of parallel, rectilinear rows of settable members, each row comprising members disposed in a rectilinear array along a corresponding path, each of said members having a face exposed at its path, each of said members being shiftable transversely of its path to dispose its aforesaid face in high and low positions, means for releasably holding the members in their respectively selected positions, a plurality of sensing means corresponding to the plurality of rows of members, each sensing means being adapted for response to the high faces of the members in the corresponding path upon movement of such sensing means along said path, an elongated conveyor device having a length at least equal to the length of a row of members multiplied by the number of such rows, the sensing means being carried by the conveyor means at localities spaced along the latter by distances at least equal to the length of a row of members, and means for advancing the conveyor means lengthwise along the aforesaid predetermined paths, so that the sensing means are successively carried along the respective corresponding rows of members for response thereto.

18. In keying apparatus, in combination, a plurality of settable members disposed in a linear array along a predetermined path and adapted to provide successive high and low faces along said path to define a message, and sensing means movable along said path for positional response to said high and low faces in succession, said sensing means including movable supporting means, means for driving the supporting means along said path, and a sensing element carried by the supporting means and having a curved sensing surface adapted to move in opposite directions at opposite ends of each high face region along the path, said sensing element being mounted loosely relative to the driving means, to provide more abrupt positional response of the element at ends of high face regions than is inherently characteristic of said curved surface.

19. Keying apparatus comprising a keying switch, a plurality of settable members disposed in a linear array and arranged to provide a series of high and low faces along a predetermined path to designate a message, a sensing device comprising a supporting member and a tubular element loosely carried thereon and adapted to engage said faces and shiftable in accordance therewith, conveyor means for moving said sensing device along said path in responsive relation to said faces, and switch-actuating means including a control structure therefor extending lengthwise of said path and adapted to be displaced by the

tubular element in accordance with the positional response thereof to high and low faces.

20. Keying apparatus for effecting alternate modifications of an electrical circuit in accordance with a series of control components defining a message, comprising a panel, a plurality of settable members arrayed along a predetermined path behind and parallel to said panel, means behind the panel controllable by the members and including a sensing element movable along the path, for controlling an electrical circuit in accordance with the characteristics of the members, said members having control characteristics respectively adapted, in series along the path, to define successive control components of a desired message, and means for repeatedly moving the sensing element along the path, to effect repeated transmission of the message, said settable members constituting a stationary array of members of which some have faces disposed in said path for predetermined engagement by the sensing element and of which others are arranged to provide spaces at intermediate localities in said path, each of said settable members including a part extending through the panel and accessible at the face of the panel, for individually setting the member to have the selected relation thereof to the sensing element and path, all of said members collectively constituting a contour defining the aforesaid message along the path, and each of said members being arranged to indicate visually at the face side of the panel its aforesaid selected relation to the path and sensing element, for visual display of the defined message.

21. Keying apparatus for effecting alternate modifications of an electrical circuit in accordance with a series of control components defining a message, comprising a plurality of individually settable members arrayed along a predetermined path and each having a control face, means controllable by the members in accordance with the positions of the control faces relative to the path, and including a sensing element movable along the path, for controlling an electrical circuit, said members having their control faces respectively disposed, in series along the path, to define successive control components of a desired message, and means for repeatedly moving the sensing element along the path, to effect repeated transmission of the message, said settable members constituting a stationary array of members arranged along a plane surface parallel to said path, some of said members having their aforesaid control faces in position for predetermined engagement by said sensing element as it moves along the path and others of said members having their control faces disposed away from such last-mentioned position to provide spaces at intermediate localities along the path, said circuit-controlling means and sensing element being disposed on the same side of said plane surface as said path, and each of said settable members including a part accessible on the other side of said surface for individually setting the member in position to have the selected relation of the control face of said member to the path.

22. Keying apparatus comprising, in combination, a plurality of individually settable members arranged in a stationary linear array along a predetermined path, electric switching means including a sensing element movable along the path, some of said members each having a face disposed in said path for engagement by the sensing element in a direction urging said element transversely of the path, others of said members

being arranged to provide spaces in said path intermediate at least certain of said faces, certain of said first-mentioned some of the members being arranged to provide short and long face structures each extending substantially continuously along the path to represent code dot and dash elements, all of said members collectively constituting a contour defining a dot and dash code message along the path, and means for moving the sensing means along the path for operation of the switching means in response to engagement of the sensing element with said member faces, to effect electrical transmission of said defined message.
